UNITED STATES PATENT OFFICE.

FRED J. WARD, OF LONG BEACH, CALIFORNIA, ASSIGNOR TO LOUIS SUTTER, OF SAN FRANCISCO, CALIFORNIA.

GAS FLOOR-HEATER.

1,334,005.

Specification of Letters Patent. Patented Mar. 16, 1920.

Application filed January 31, 1919. Serial No. 274,320.

To all whom it may concern:

Be it known that I, FRED J. WARD, a citizen of the United States, residing at Long Beach, in the county of Los Angeles and State of California, have invented new and useful Improvements in Gas Floor-Heaters, of which the following is a specification.

My invention relates to gas floor heaters and consists of the novel features herein shown, described and claimed.

An object of my invention is to make a gas floor heater of reduced size and increased capacity.

Another object of my invention is to make a gas floor heater of a few simple pieces easily made and readily assembled.

Another object of my invention is to make a radiator for a gas floor heater which will occupy comparatively small space and have a large heating capacity.

Figure 1 is a vertical central section of a gas floor heater embodying the principles of my invention.

Fig. 2 is a perspective upon a reduced scale of the gas floor heater removed from the floor.

Fig. 3 is a fragmentary vertical sectional detail on the line 3—3 of Fig. 1 and showing the gas cocks for controlling the pilot and the main burner.

Fig. 4 is a perspective of the top plate of the radiator.

Fig. 5 is a perspective of the central radiating element.

Fig. 6 is a perspective of the base of the radiator.

Fig. 7 is a perspective of the bottom through which the burners discharge into the radiator and upon which the radiator rests and upon which the radiator base shown in Fig. 6 fits.

Fig. 8 is an enlarged cross sectional detail on the line 8—8 of Fig. 4.

Fig. 9 is an enlarged cross sectional detail on the line 9—9 of Fig. 6.

Fig. 10 is a perspective of a match holder for lighting the furnace.

A floor 1 is built upon joists 2 and a rectangular opening 3 is made through the floor 1 between two joists. An outer shell 4 is straight up and down, rectangular in plan, and has an out-turned flange 5 at its upper end all the way around so that the

shell fits closely in the hole 3 and the flange rests upon the floor 1 around the hole. The shell 4 is preferably formed of heavy galvanized iron. A layer of asbestos paper 6 is pasted to the outer face of the outer shell 4. 60

A gas feed pipe 7 has a union 8 upon its end. A T 9 is connected to the other end of the union from the pipe 7. A nipple 10 extends outwardly from the T 9 and a cap 11 is mounted upon the lower end of the nipple 10 to make a drip pot. A pipe 12 extends upwardly from the T 9 inside of one wall of the outer shell 4. 65

A double gas cock fitting 13 is connected to the upper end of the pipe 12. The double gas cock fitting 13 consists of a female nipple 14 screwed upon the end of the pipe 12, a gas cock construction 15 extending one way from the nipple 14, and a gas cock construction 16 extending the other way 75 from the nipple 14, and ears 17 through which screws 18 are inserted to secure the fitting against the inner face of the outer shell 4 directly below its upper edge. Movable valve members 19 and 20 have sockets 80 with openings to receive a key 21 so that the key may be inserted into either one of the valves and the valve operated and the key removed.

A reinforcing plate 22 is secured against 85 the inner face of the outer shell 4 by rivets 23 and the screws 18 are inserted through the ears 17 and tapped into the plate 22. A main supply pipe 24 is connected to the valve construction 16 and extends downwardly to main burners 25 and 26 and a pilot light pipe 27 is connected to the valve construction 15 and extends downwardly to a pilot burner 28 so that by placing the key 21 in the valve 19 the pilot burner may be 90 controlled and so that by placing the key 21 in the valve 20 the main burners may be controlled. 95

A bottom 29 is inserted upwardly into the lower end of the outer shell 4 and secured in 100 place by bolts 30. In assembling the parts the bottom 29 is placed in position before the pipes 20, 24 and 27 are placed in position. The details of the bottom 29 are as follows: The bottom 29 is preferably a casting and comprises a rectangular flat plate 31, and a flange 32 extending downwardly all the way around from the edge of the plate 31. A rectangular opening 33 is 105

formed through the plate 31, there being a rib 34 extending upwardly all the way around the opening 33 a short distance outside of the edge of the opening, thereby 5 forming a ledge 35 all the way around the edge of the opening. A wall 36 extends downwardly from the plate 31 in vertical alinement with the rib 34 to form a housing around the burners 25, 26, and 28, said housing being open at the bottom to provide a free circulation of air upwardly through the housing around the burners to the combustion chamber. A circular opening 37 is formed through the plate 31 at one end of 10 the opening 33. An annular rib 38 extends upwardly from the plate 31 around the opening 37 a short distance outside of the edge of the plate to form a ledge 39. Bolt holes 40, 41, 42 and 43 are formed through 15 the plate 31.

The details of a radiator base 44 shown in Fig. 6 includes the parts 45 to 74 and are as follows: The base 44 is an integral casting and has a rectangular housing 25 45 open at the top and bottom and fitting upon the ledge 35. A circular housing 46 is open at the top and bottom and fits upon the ledge 39 and a web 47 connects the circular housing 46 to the rectangular housing 45. A flue nipple 48 extends horizontally from the housing 46 at the opposite side from the housing 45. Flue bottoms 49, 50 and 51 extend horizontally outwardly from the upper edge of the wall 52 of the 30 housing 45 and similar flue bottoms 53, 54 and 55 extend horizontally outwardly from the upper edge of a wall 56 of the housing 45. A flue bottom 57 extends from the upper edge of a wall 58 of the housing 45 over 35 the web 47 and flue bottoms 59 and 60 extend outwardly from the upper end of the housing 46 in line with the flue bottoms 49, 50 and 51 and flue bottoms 61 and 62 extend horizontally outwardly from the upper 40 end of the housing 46 in line with the flue bottoms 53, 54 and 55. The flue bottoms 49, 50, 51, 59, 60, 62, 61, 55, 54 and 53 are evenly spaced apart thereby forming air 45 passages 63, 64, 65 and 66 one side of the casting and similar air passages 67, 68, 69 and 70 on the other side of the casting. Flanges 71 and 72 extend upwardly from the upper edge of an end wall 73 of the housing 45, thereby forming a channel 74 50 between the flanges. The flanges 71 and 72 are continuous extending upwardly along the edges of the flue bottom 49, then along the edge of the wall 52, then along the outer edge of the floor bottom 50, and so on all 55 the way around the casting.

The details of the central radiating element 75 as shown in Fig. 5 are as follows: A radiating element 75 is made of sheet metal and preferably consists of two mating pieces 76 and 77. The main part of the

piece 76 is bent in and out to form hot air flues 78, 79, 80, 81 and 82 fitting in the channel 74 around the flue bottoms 53, 54, 55, 61 and 62, and forming channel shaped air passages 83 between the hot air flues in line 70 with the air passages 67, 68, 69 and 70, and the ends of the plate extending half way across the ends of the casting 44. In a like manner the piece 77 is bent in and out to form hot air flues 84, 85, 86, 87 and 88 fitting 75 in the channel 74 along the edges of the flue bottoms 49, 50, 51, 59 and 60, and forming channel shaped air passages 89 between the hot air flues 84, 85, 86, 87 and 88 in line with the air passages 63, 64, 65 and 66. 80

A partition 90 consists of a flat plate inserted in the hot air flues 81 and 87 against the walls of the air passages 83 and 89 which are between the hot air flues 80 and 81 and 86 and 87 and held in place by bolts 85 or rivets 91. The partition 90 is cut short and extends from the bottom of the radiating element 75 nearly to the top thereby leaving a hot air passage 92 over the top of the partition. The pieces 76 and 77 are connected together by vertical seams 93 and 94. 90

The details of the top plate 95 of the radiator shown in Fig. 4 are as follows: A top plate 95 is a casting and consists of a main body 96 having notches 97 and 98 extending 95 from its side edges, an opening 99 extending through one end and surrounded by an upwardly projecting annular ring 100 and bolt holes 101, 102, 103 and 104 formed through its corners. The notches 97 are in line with the air passages 89 in the radiating element 75 and the air passages 63, 64, 65 and 66 in the casting 44, and projections 105 between the notches 97 are in line with the hot air flues 84, 85, 86, 87 and 88 and in line with the flue bottoms 49, 50, 51, 59 and 60. In a like manner projections 106 between the notches 98 are in line with the hot air flues 78, 79, 80, 81 and 82 and in line with the flue bottoms 53, 54, 55, 61 and 62, and the 100 bolt holes 101, 102, 103, and 104 are in line with the bolt holes 40, 41, 42 and 43 in the casting 29. A lower face 107 of the top plate 95 is practically a mate to the upper face of the casting 44. Flanges 108 and 109 105 extend downwardly all the way around the edge of the casting 95 and form a channel 110 in which the upper edge of the radiating element 75 fits. The lower edge of the radiating element 75 fits in the channel 74 110 in the casting 44.

Stove bolts 111 are inserted downwardly through the bolt holes 101, 102, 103 and 104 and through the bolt holes 40, 41, 42 and 43 and nuts are placed upon the lower ends 115 of the bolts to hold the outer shell bottom 29, the base 44, the radiating element 75 and the top plate 95 securely together.

A cap 112 fits upon the annular ring 100 and the cap 112 consists of an inner member 130

113 fitting within the annular ring 100; an outer member 114 fitting outside of the ring 100; a mica plate 115 fitting between the members 113 and 114; and a handle 116, all 5 the parts being secured together by bolts 117. The member 113 is L-shaped in cross section and has a flat upper face upon which the mica plate 115 rests. The member 114 has a flat lower face fitting upon the mica 10 plate 115 and extends downwardly and outwardly to form a channel 118 to receive the ring 100.

A register frame 119 fits upon the floor 1 over the flange 5 and ears 120 extend inwardly from the frame and screws 121 are 15 inserted downwardly through the ears and tapped into brackets 122 secured to the inner face of the outer shell 4. A grate 123 extends inwardly from the frame 119 all the 20 way around to make a rectangular opening 124, there being a ledge 125 extending inwardly all the way around from the opening 124. An intermediate casing 126 is formed of sheet metal and the upper end of the casing 126 is reduced in size and inserted upwardly through the opening surrounded by the ledge 125 and the upper edge of the casing is turned outwardly to form a flange 127 fitting upon the ledge 125 so as to support 25 the casing 126. The casing 126 extends downwardly to a point half way between the top and the bottom of the casting 44, thereby forming a cold air passage 128 leading downwardly through the grate 123 between 30 the outer shell 4 and the intermediate casing 126 and a heating chamber 129 leading upwardly outside of the radiator 75 and inside of the intermediate casing 126. A flue 130 is attached to the nipple 48 and extends 35 outwardly through the outer shell 4 and upwardly to any desired position. A register grate 131 is loosely mounted within the grate 123 and upon the flange 127 to cover the radiator so that when desired the register 131 40 may be removed and the cap 112 removed to light the pilot 28.

For the purpose of lighting the pilot 28 I employ a match holder 132 formed of wire comprising a handle 133, a long stem 134 50 and a coil 135. A lighted match 136 may be pressed between the strands of the coil 135, the handle 133 manually grasped and the match holder inserted downwardly through the cap hole 99, then the key 21 may 55 be operated to turn on the gas to the pilot 28. As soon as the pilot 28 ignites the cap 112 may be replaced and the grate 131 replaced, then the key 21 may be operated to turn on the gas through the pipe 24 to the burners 60 25 and 26. The fresh air will pass upwardly around the burners within the wall 36, then the hot air and products of combustion will pass upwardly through the housing 45 and upwardly through the radiator 75 above the 65 housing 45 and through the hot air passage

92 over the top of the partition 90 and downwardly through the radiator to the housing 46, and then outwardly through the nipple 48 and through the flue 130. Fresh air will pass upwardly through the opening 37 to the 70 housing 46 and mix with the products of combustion and pass to the flue and this introduction of cold air into the products of combustion will improve and stimulate the draft and at the same time it will steady the 75 draft and remove or eliminate the pulsations caused by the wind. The heating element 75 presents the largest practical amount of heating surface within the space allowed and the fresh air passing from the room downwardly through the passage 128 and under the lower edge of the intermediate casing 126 will pass over the bottom 29 around the casting 44 and will pass upwardly inside of the casing 126 and through the passage 129 80 and around the radiating element 75 and top plate 95 and then the hot fresh air will pass upwardly through the register 131 to warm the room. By removing the screws 121 the grate 123 carrying the intermediate 85 casing 126 and the grate 131 can be removed to provide access to the interior of the outer shell 4 and the furnace can be thoroughly cleaned from the floor 1 and the parts 19 and 20 can be oiled and repaired. 90

Various changes may be made without departing from the spirit of my invention as claimed.

I claim:

1. A gas floor heater comprising an outer shell open at the top and bottom; a bottom mounted in the lower end of the outer shell and comprising a casting forming a rectangular flat plate, a rectangular opening through the plate, a rib extending upwardly 100 around the rectangular opening a short distance outside of the edge thereby forming a ledge, a wall extending downwardly from the plate in vertical alinement with the rib and forming a housing open at the bottom, 105 a circular opening through the plate near one end of the rectangular opening, an annular rib extending upwardly from the plate around the circular opening a short distance outside of the edge and forming a ledge; 110 and a radiator base fitting upon the ledges around the openings, said radiator base comprising an integral casting forming a rectangular housing open at the top and bottom, a circular housing beside the rectangular housing and open at the top and bottom, 115 a web connecting the two housings, a flue nipple extending horizontally from the circular housing at the opposite side from the rectangular housing, flue bottoms extending 120 horizontally outwardly from the upper edge of one side wall of the rectangular housing, similar flue bottoms extending horizontally 125 outwardly from the upper edge of the other side wall of the rectangular housing, a flue 130

bottom extending horizontally from the upper edge of one end wall of the rectangular housing over the web, and flue bottoms extending both ways from the upper end of the circular housing in line with the first flue bottoms, all of said flue bottoms being evenly spaced apart and of even size and forming a seat for a radiator; a radiating element mounted upon the radiator base and forming an up passage from the burner housing and a down passage to the second housing and forming flues extending upwardly from the flue bottoms of the radiator base; a top for the radiating element; a register mounted above the top; and an intermediate housing extending downwardly from the register around the radiating element.

2. In a gas floor heater; an outer shell open at the top and bottom; a bottom mounted in the lower end of the outer shell, there being a burner opening through the bottom and a cold air opening through the bottom; a radiator base mounted upon the bottom and comprising an integral casting forming a rectangular housing open at the top and bottom, a circular housing beside the rectangular housing open at the top and bottom, a web connecting the two housings, a flue nipple extending horizontally from the circular housing at the opposite side from the rectangular housing, flue bottoms extending horizontally outwardly from the upper edge of one side wall of the rectangular housing, similar flue bottoms extending horizontally outwardly from the upper edge of the other side wall of the rectangular housing, a flue bottom extending horizontally from the upper edge of one end wall of

the rectangular housing over the web, and flue bottoms extending both ways from the upper end of the circular housing in line with the first flue bottoms, all of said flue bottoms being evenly spaced apart and of even size and forming a seat for a radiator; a radiating element mounted upon the radiator base and forming an up passage from the burner housing and a down passage to the second housing and forming flues extending upwardly from the flue bottoms of the radiator base; a top for the radiating element; a register mounted above the top; and an intermediate housing extending downwardly from the register around the radiating element.

3. In a gas floor heater, a radiator including an integral casting open at its top and bottom and having a pair of housings with a web connecting same, spaced flue bottoms extending outwardly from opposite sides of the housings, a radiator casing and flues seated on the flue bottoms, a radiator top seated on the casing, and a burner alined with one of the housings.

4. In a gas floor heater, a radiator including an integral casting open at its top and bottom and having a pair of housings with a web connecting same, spaced flue bottoms extending outwardly from opposite sides of the housing, a radiator casing and flues seated on the flue bottoms, a radiator top seated on the casing, a partition seated on the top of the web and spaced below the top of the radiator top, and a burner alined with one of the housings.

In testimony whereof I have signed my name to this specification.

FRED. J. WARD.
